US00D788627S

(12) **United States Design Patent** (10) **Patent No.:** **US D788,627 S**
(45) **Date of Patent:** **** Jun. 6, 2017**

(54) **WEARABLE DEVICE**

(71) Applicant: **LG ELECTRONICS INC.**, Seoul (KR)

(72) Inventors: **Soonhyun Park**, Seoul (KR); **Cheolwoong Shin**, Seoul (KR); **Hongsik Kim**, Seoul (KR); **Jinki Min**, Seoul (KR); **Seunghwan Song**, Seoul (KR); **Byunghyun Yi**, Seoul (KR); **Jiyoun Cha**, Seoul (KR)

(73) Assignee: **LG ELECTRONICS INC.**, Seoul (KR)

(**) Term: **15 Years**

(21) Appl. No.: **29/529,912**

(22) Filed: **Jun. 11, 2015**

(30) **Foreign Application Priority Data**

Dec. 12, 2014 (KR) 30-2014-0060833

(51) **LOC (10) Cl.** **11-01**

(52) **U.S. Cl.**

USPC **D11/5**; D14/344

(58) **Field of Classification Search**

USPC ..... D11/1-39; D10/31, 32, 38, 39, 65, 70, D10/78, 97, 98; D14/344; D24/167, 186 CPC . (57) **CLAIM**

The ornamental design for a wearable device, as shown and described.

DESCRIPTION

FIG. 1 is a perspective view of a wearable device showing our new design;

FIG. 2 is a front view thereof, the rear view being a mirror image thereof;

FIG. 3 is a left side view thereof;

FIG. 4 is a right side view thereof;

FIG. 5 is a top plan view thereof;

FIG. 6 is a bottom plan view thereof;

FIG. 7 is another front view thereof, showing the wearable device in a closed configuration; and,

FIG. 8 is another top plan view thereof, showing the wearable device in a configuration of use.

The broken lines in FIG. 8 show environmental structure only and form no part of the claimed design.

1 Claim, 7 Drawing Sheets
